UNITED STATES PATENT OFFICE.

EMIL ERICKSSON, OF CHICAGO, ILLINOIS, ASSIGNOR TO WM. A. FIELD COMPANY, OF CHICAGO, ILLINOIS, A CORPORATION OF ILLINOIS.

MACHINE FOR CORRECTING PRINTING PLATES.

Application filed March 13, 1924. Serial No. 698,930.

This machine is designed for the purpose of simultaneously pressing out inequalities in the printing surface of a printing plate and shaving the back surface, so that as the printing plate emerges from the machine it will be true, plane and smooth, and of equal thickness throughout.

With this end in view the machine is provided with spring pressed shoes which, bearing against the reverse surface of the printing plate, serve to level down the printing surface of the plate into plane contact with the supporting plate of the machine, thereby correcting the printing surface, and these pressers act in conjunction with a shaving knife which serves to shave off the inequalities which are all transferred and pressed up into the reverse surface. The conjoint action of these instrumentalities completes the action on the plate, so that the plates may be rapidly fed into the machine and corrected without the necessity for performing separate and distinct operations of the character commonly employed at the present time in the correction of plates.

The invention also relates to the means provided for securing exact adjustment of the mechanisms, so that the resultant thickness of the plate can be gauged to exact dimensions, which is an important feature in the correction of plates for printing purposes.

In the drawings:

Figure 1 is a plan view of the machine as a whole;

Fig. 2 is a longitudinal sectional elevation thereof;

Fig. 3 is a diagonal transverse sectional view showing the pressers partly in elevation and partly in section;

Fig. 4 is a sectional detail of one of the pressers and the shaving knife; and

Fig. 5 is a perspective showing the shaving knife on the reverse surface of the printing plate.

The machine as a whole comprises a base 10 which supports a standard 11 of rugged construction, which standard at its upper edge is provided with flanges 12 to which is bolted a box like housing 13 comprising a base wall 14, side walls 15 and a top cross wall 16, which latter extends only over a portion of the housing.

The housing also comprises a front end wall 17 which connects the two side walls

15. The front wall has formed along its upper inner edge a flange 18 in parallel relation with the top cross wall 16, and the rectangular space thus provided between the side walls 15 furnishes an opening for the 60 housing of a vertically adjustable table 19 upon which the printing plate 20 is laid face downwards.

The table 19 is provided with depending sides 21 which bear against the inner faces 65 of the side walls 15 and are guided thereby. The lower edges of the table sides 21 are diagonally stepped to afford bearing edges 22, offset with respect to one another, which edges are supported upon the similarly formed diagonally stepped edges 23 of a pair of adjusting slides 24 which are united by a cross web 25.

The cross web 25 at its front end has formed thereon a socket block 26 which has 75 threaded therein the inner end of an adjusting screw 27, which terminates in a spindle 28 which is journaled within the journal block 29 carried by the front end wall 17 of the housing. A hand wheel 30, provided 80 on its periphery with graduations 31, serves to impart rotation to the adjusting screw 27 which in turn imparts longitudinal movement to the slides 24, which latter, by reason of the diagonally stepped arrangement of 85 their acting edges, serve to impart vertical movement, in graduated degree, to the table top 19, so that the elevation thereof can be adjusted to an exact degree.

The side walls 15 of the housing are provided along their upper edges with guide flanges 32 which afford guideways for a pair of riders 33 which, as shown in Fig. 1, are arranged one in advance of the other on opposite sides of the housing. The riders 95 serve as supports for a diagonally arranged front bridge 34 and a diagonally arranged rear bridge 35, which bridges are of rugged construction and extend across the surface 100 of the table in elevated relation with respect thereto.

The front bridge 34 is provided with a plurality of bores 36, each of which is shouldered at its lower end 37 and is closed at its upper end by means of a screw plug 38 provided with a smooth center bore 39. The bore serves as a guide for the stem 40 of a presser shoe 41, a coil spring being housed 105 within the bore 36 to exert a downward pressure against a collar 43 on the stem. 110

The tension of the spring can be regulated by adjustment of the screw plug 38, which is provided at its upper end with a squared head 44.

5 Each of the shoes 41 is rounded on its under surface and terminates in a rearwardly extending toe 45, and the entire line of toes extend into close proximity to a shaving knife 46, which also extends in oblique relation to the table top and is supported in oblique relation upon the rear face of the forward bridge 35. The knife is provided with a plurality of vertical slots 47, each of which receives a clamping bolt 48 to clamp the knife in position. Vertical adjustment of the knife may be effected by the turning of a series of adjusting screws 49 which are entered through a plurality of overhanging brackets 50 and bear against the upper edge 10 of the knife.

20 Each of the riders 33 has secured thereto a rearwardly extending rack 51, which racks extend in parallel relation along the upper edge of the housing, and each of the racks is in mesh with a pinion 52, which pinions are carried by a transverse shaft 53 journaled within brackets 54 secured to the sides of the housing. At one end of the shaft is a large gear wheel 55 which is driven 25 through a train of gearing 56 driven by a motor 57 supported upon the base of the machine.

30 In order to heat the table which supports the printing plates, and thereby render the same more pliable, a plurality of gas burners 58 are provided which are located directly beneath the adjustable table 19 upon which the plate is supported. In order to prevent displacement of the plate while being corrected, a stop 59 is provided against 35 which the front end of the printing plate is abutted.

40 In use the motor is set in motion to retract the riders and bridge plates which in unison comprise, what might be properly termed, a carriage, and after the carriage has been retracted to the degree required to afford space for the positioning of the printing plate against the stop 59, the motor is stopped, and the table 19 is elevated by the 45 turning of the gear wheel to bring the surface of the table into a predetermined space relation to the edge of the shaving knife.

45 The presser shoes are regulated to afford the required degree of pressure and after the plate has been heated to the desired degree by contact with the table surface, the motor is started in the reverse direction to move the carriage toward the front. As the presser shoes engage the plate they will exert the 50 degree of pressure required to press the printing surface of the plate into firm contact with the plane surface of the table, so that all inequalities of the printing surface 55 will be eliminated and will be trans-

ferred to the rear or upper surface of the plate. As the carriage is moved forwardly, the rear surface will be shaved, so that all inequalities will be eliminated and the plate 60 fully corrected and leveled down to the desired thickness.

65 The mechanism is one which permits a large number of plates to be corrected in rapid succession and substantial uniformity, and obviates repeated handlings of the plates, 70 which not only involve a waste of time, but also involve a risk of marring the plates during the successive stages of correction.

75 The use of a considerable number of individual pressers, permits each portion of the plate to be momentarily contacted, so that local inequalities in the printing surface will be smoothed out without the application of undue pressure which might 80 tend to mar the printing surface, and the space relation of the presser shoes permits the metal of the plate to readily adapt itself to the compressive influence of the pressers.

85 Although the invention has been shown in form adapted for the correction of plane flat plates, the principles involved are applicable to the correction of cylindrical plates, and will, therefore, be understood in the claims, that where reference is made to a 90 relative longitudinal movement between the carriage and the table, that the term longitudinal is intended to embrace and include not only straight line movements but movements of an arcuate character such as 95 to maintain parallelism between the surface 100 of the plate and the correcting tools which coact therewith.

I claim:

1. In a machine for correcting printing plates, the combination of a standard, a longitudinally disposed housing supported by the standard, a table slidably mounted within the housing in position to permit vertical movement of the table, means for vertically adjusting the table with respect to the housing, said means including a slide plate having an oblique surface contact with an obliquely configured portion of the table, and means for longitudinally adjusting the slide plate, a carriage slidably mounted with respect to the housing and table carried thereby, said carriage including a bridge portion spanning the table and guide members slidably engaging the housing to admit of longitudinal adjustment of the carriage, a plurality of spring backed pressers carried by the carriage, a knife carried by the carriage in co-acting relation with the pressers, and means for effecting longitudinal movement of the carriage, substantially as described.

120 2. In a machine for correcting printing plates, the combination of a standard, a longitudinally disposed housing supported by the standard, a table slidably mounted 125

- within the housing in position to permit vertical movement of the table, means for vertically adjusting the table with respect to the housing, said means including a slideable 5 plate having an oblique surface contact with an obliquely configured portion of the table, and means for longitudinally adjusting the slide plate, a carriage slidably mounted with respect to the housing and table carried thereby, said carriage including a bridge portion spanning the table and guide members slidably engaging the housing to admit of longitudinal adjustment of the carriage, a plurality of spring backed pressers carried by the carriage, a knife carried by the carriage in co-acting relation with the pressers, and means for effecting longitudinal movement of the carriage, said means including a rack secured to and longitudinally 10 extending from the carriage, and a gear meshing with said rack, substantially as described.
3. In a machine for correcting printing plates, the combination of a standard, a housing supported by the standard and provided with an aperture therein, a table mounted within said aperture and adapted for vertical adjustment therein, means for vertically adjusting the table with respect to the housing, said means including a stepped flange secured to the table, the steps thereof being arranged to present obliquely disposed contact edges downwardly, a slide plate co-acting with said stepped flange and provided with a series of steps disposed to present oblique contacting edges upwardly in contact with the stepped surfaces of the flange, screw means for advancing and withdrawing the slide plate to impart vertical adjustment to the table, a carriage provided with a bridge portion obliquely spanning the housing and table carried thereby and provided with guide portions adapted to slidably engage the housing on opposite sides of the table, a plurality of spring backed pressers carried by the carriage, a knife carried by the carriage in co-acting relation with the pressers, means for effecting longitudinal movements of the carriage with respect to the table surface, said means including a pair of parallel racks longitudinally extending from the carriage in parallel relation to the plane of movement of the carriage, a shaft extending across the racks, and gear members on said shaft engaging the respective racks, substantially as described. 15 20 25 30 35 40
- the housing on opposite sides of the table, a plurality of spring backed pressers carried by the carriage, a knife carried by the carriage in co-acting relation with the pressers, and means for effecting longitudinal movements of the carriage with respect to the table surface, substantially as described. 45 50 55 60 65 70 75 80
4. In a machine for correcting printing plates, the combination of a standard, a housing supported by the standard and provided with an aperture therein, a table mounted within said aperture and adapted for vertical adjustment therein, means for vertically adjusting the table with respect to the housing, said means including a stepped flange secured to the table, the steps thereof being arranged to present obliquely disposed contact edges downwardly, a slide plate co-acting with said stepped flange and provided with a series of steps disposed to present oblique contacting edges upwardly in contact with the stepped surfaces of the flange, screw means for advancing and withdrawing the slide plate to impart vertical adjustment to the table, a carriage provided with a bridge portion obliquely spanning the housing and table carried thereby and provided with guide portions adapted to slidably engage the housing on opposite sides of the table, a plurality of spring backed pressers carried by the carriage, a knife carried by the carriage in co-acting relation with the pressers, means for effecting longitudinal movements of the carriage with respect to the table surface, said means including a pair of parallel racks longitudinally extending from the carriage in parallel relation to the plane of movement of the carriage, a shaft extending across the racks, and gear members on said shaft engaging the respective racks, substantially as described. 65
